UNITED STATES PATENT OFFICE.

WALTER EDWIN TRENT, OF NEW YORK, N. Y., ASSIGNOR TO TRENT PROCESS CORPORATION, OF NEW YORK, N. Y., A CORPORATION OF DELAWARE.

CARBONIZING PROCESS.

Application filed March 11, 1925. Serial No. 14,732.

The invention relates to improvements in a process and apparatus for carbonizing coal and oil mixtures.

The invention relates to the broad process described in my co-pending application Serial No. 12,128, filed February 27, 1925, wherein replaceable elements are heated and then applied to receivers containing coal and oil to transmit the stored heat by radiation to carbonize the green fuel therein.

It is an object of the present invention to improve the process above mentioned, said improvements consisting in the low temperature carbonization of coal and oil mixtures in either bulk or preformed charges by utilizing heat storage elements applied to a receiver above the green charge therein so that the products of distillation rising in the receiver must contact with the hot storage element thereabove and then descend through the charge, imparting the excess heat of the gases to the fuel therein prior to the discharge of the gases from the bottom or lower part of the receiver.

The invention furthermore contemplates an improved apparatus wherein a receiver is provided with a perforated lower wall upon which fuel charges rest, while the upper part of the receiver is fashioned to receive a removable heat storage element constituting in effect a closure therefor.

In the accompanying drawings,—

Figure 1 designates a diagrammatic view of the distilling retort with the receiver.

Fig. 2 discloses a detailed view of the receiver with the heat storage element removed therefrom.

Fig. 3 is a modified form of container.

Referring now more particularly to the drawings, the numeral 1 designates a distilling retort in which an endless conveyor 2 travels. This conveyor may be composed of connected links or any approved construction. The conveyor at one end travels around the sprocket 3 located in the retort 1 while the opposite end of the conveyor travels around the sprocket 4 disposed outside of the retort. This sprocket 4 may be driven in any suitable manner to impart motion to the conveyor. It will be understood that the conveyor comprises a pair of separated endless chains. Suspended be-

tween these chains are a series of pans 5 of a structure shown in detail in Fig. 2. Each pan has a series of apertures 6 in the bottom thereof for the discharge of gases, as will be hereinafter described. The pans can be of any desired capacity, the side walls 7 thereof being provided with slideways 8 to slidably receive removable heat storage elements 9 which constitute in effect a closure for the pans. The side walls 7 are slightly higher than the end walls 10 of the pan.

The heat storage elements 9 are heated in any suitable furnace or retort and to the desired temperature. As a pan passes the sprocket 4 the bulk mixtures of coal and oil of a somewhat plastic consistency, or preformed masses of coal and oil which have been molded or otherwise shaped, are introduced to the pan. The pan can be substantially filled with this green material. One of the heat storage elements 9 is then placed on the pan by being positioned in the slideways 8 formed therein. The pan then enters the distilling chamber 1 where heat is imparted to the green mass therein by reason of its heat storage element 9. The element 9 is preferably composed of cast iron or other like material and is heated to a temperature sufficient to raise the temperature of the fuel in a pan to, say, 600° centigrade. This low temperature carbonization occurs during the travel of a pan through the retort 1. During this travel as the green fuel undergoes distillation the vapors rise and contact with the under surface of the heat storage element 8, being highly heated due to such contact, and are then compelled to descend through the charge of material therein, imparting the excess heat to the charge before escaping through the openings 6 in the bottom of each pan. By providing the heat storing element above the fuel in the pan with a gas outlet at the bottom thereof, a high heat efficiency may be obtained and the oils and gases are subjected to a pronounced cracking while the resulting fuel is more uniformly carbonized. The vapors driven from the fuel discharge through the vapor outlet 11 for further treatment and collection. Any liquid products driven from the fuel collect in the

trough 12 beneath the conveyor, being withdrawn from this trough through a valve-controlled outlet pipe 13. When a charge has passed through the distilling oven and reaches the point α , which constitutes the unloading zone, the removable heat storage element 9 is taken from its pan and the contents of the pan discharged. This element is then re-heated for further use while the pan travels around the sprocket 4 and receives an additional supply of green fuel. When so supplied a highly heated storage element 9 is then applied to the pan for travel through the distilling oven therewith. The carbonized contents of each pan discharge into the trough 13' at the time the heat storage element is removed.

In carrying out my process I either introduce to a pan as it is about to enter the distilling oven a bulk mixture of coal and oil, or a series of preformed bonded charges of coal and oil of any contour. Such charges may be round, square, or otherwise. One of the heat storage elements 9, having been heated to a high temperature of, say, 800° centigrade, is then inserted in the pan, being received by the guideways 8. This heat storage element is sufficiently hot to apply to the green material in the pan a temperature of, say, 600° centigrade, if low temperature carbonization is being practiced. Obviously higher temperatures can be employed if a coke-like product is desired. The heat storage elements can be heated to any temperature found preferable, in keeping with the product to be produced.

During travel through the distilling chamber the valuable by-products are removed from the coal and such products are discharged through the vapor and gas outlet for treatment and collection. Condensed oils that may drip from the coal are collected in the trough 12 as hereinbefore described. It will be understood that during the distillation of a charge of material in a pan the vapors naturally ascend and thereby contact with the under surfaces of one of the hot storage elements, which serves to superheat these vapors and gases. The so heated vapors and gases must then pass down through the body of material in the pan and escape through the outlets 6 located therein. This heat treatment of the gases and vapors also serves to crack certain of the vapors into low boiling point oils, while at the same time applying a maximum temperature to the solid residue remaining in the pans.

In Fig. 3 of the drawings I have shown another embodiment of the invention wherein a container 15 having apertures 16 near its bottom is provided. This container has slideways 17 receiving removable heat storage elements 18. The interior of the container receives the green material to under-

go treatment. In this process the container need not travel through a distilling oven but may be stationary in any suitable heat insulated retort. That is to say, the container may be filled and receive its heat storage element after which it is applied to a retort to remain therein until the material undergoes carbonization. After the desired time of treatment has elapsed the container can be removed from the retort or other receiver, the heat storing element being then detached from the container and the carbonized contents collected. It will be understood that if such a container is used the products of distillation issuing therefrom are discharged from the retort and collected in any approved manner.

Having thus described the invention, what I claim is:

1. A process for carbonizing coal, consisting in introducing supplies of coal to individual receivers, in moving the receivers through a carbonizing zone, in applying heat to the coal in each receiver by radiation from a heat storage element attached to each receiver above the fuel charge to heat the fuel charge to a carbonizing temperature, and in discharging vapors and gases from the lower portion of each receiver. 85

2. A carbonizing process consisting in advancing individual charges of coal through a retort, in applying heat to each individual charge by independent heat transferring elements moving through said retort in speed synchronism with said charges and to heat 95 said charges to a carbonizing temperature, and in discharging vapors and gases generated from each charge at a point substantially below such elements. 100

3. An apparatus for carbonizing materials comprising a series of connected receptacles, each adapted to receive fuel charges, means for moving said receptacles in an endless path through a retort, each receptacle having a bottom wall provided with 105 discharge openings extending therethrough, side and end walls connected with the bottom wall, longitudinal guideways in said side walls, and a detachable heat storage element movable in said guideways to provide 110 a closure for each receptacle and to apply heat to the contents thereof. 115

4. An apparatus for carbonizing materials, comprising a receptacle having a bottom wall, said wall having a plurality of openings extending therethrough, side and end walls for the receptacle, and a combined top wall and heating element slidably connected with the side walls of the receptacle. 120

5. An apparatus for carbonizing materials comprising a receptacle having a bottom, and side and end walls, a plurality of discharge openings extending through one of said walls of the receptacle, guideways formed in other walls of the receptacle, and 130

a combined closure and heat storage plate slidably engaging said guideways.

6. A carbonizing process comprising applying fuel charges to a receptacle, in heating said charge to a temperature sufficient to effect carbonization thereof by placing a heat storage element over the charge in the

receptacle to which the self contained heat of said element is transmitted, and in discharging vapors and gases from the receptacle at a point below the fuel charge contained therein. 10

In testimony whereof I affix my signature.
WALTER EDWIN TRENT.
